Primary Examiner—Paula A. Mortimer

(74) Attorney, Agent, or Firm—Dorsey & Whitney LLP

(57) **CLAIM**

The ornamental design for a flosser tip, as shown and described.

DESCRIPTION

FIG. 1 is an isometric view of a flosser tip showing our new design;

FIG. 2 is a top plan view thereof, the bottom plan view being a mirror image thereof;

FIG. 3 is a front elevation view thereof;

FIG. 4 is a left side elevation view thereof;

FIG. 5 is a right side elevation view thereof; and,

FIG. 6 is a rear elevation view thereof.

UNITED STATES PATENT AND TRADEMARK OFFICE
CERTIFICATE OF CORRECTION

PATENT NO. : Des 437,976 S
DATED : February 20, 2001
INVENTOR(S) : Ravikumar S. Narayanan et al.

Page 1 of 2

It is certified that error appears in the above-identified patent and that said Letters Patent is hereby corrected as shown below:

Title page.

Fig. 1. should be replaced with attached Fig. 1 on drawing sheet 1/2; and

Drawings.

Drawing sheet 1/2 should be replaced with attached drawing sheet 1/2.

Signed and Sealed this

Twenty-seventh Day of August, 2002
